US0D1106281S

(12) **United States Design Patent** (10) **Patent No.:** **US D1,106,281 S**
(45) **Date of Patent:** **** Dec. 16, 2025**

(54) **BODY PORTION FOR AGRICULTURAL VEHICLE**

(71) Applicant: **Deere & Company**, Moline, IL (US)

(72) Inventors: **Brian L. Andersen**, Reinbeck, IA (US); **Yogesh K.**, Gurugram (IN); **Ryan G. Brown**, Cedar Falls, IA (US); **Samir M. Mahadik**, Pune (IN)

(73) Assignee: **DEERE & COMPANY**, Moline, IL (US)

(**) Term: **15 Years**

(21) Appl. No.: **29/877,841**

(22) Filed: **Jun. 13, 2023**

(30) **Foreign Application Priority Data**

Dec. 20, 2022 (EM) 015006881

(51) **LOC (15) Cl.** **15-03**

(52) **U.S. Cl.**

USPC **D15/31**

(58) **Field of Classification Search**

USPC D15/10, 14, 15, 17, 20, 22, 23, 26, 28, D15/30-33; D12/82, 93, 99, 164, 173, D12/181; D34/37; D21/431, 533, 537, D21/556, 560, 562

(57) **CLAIM**

The ornamental design for a body portion for agricultural vehicle, as shown and described.

DESCRIPTION

FIG. 1 is a front, right perspective view of a body portion for agricultural vehicle according to our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The dashed lines in the figures depict environment subject matter that forms no part of the claimed design.

1 Claim, 7 Drawing Sheets
